UNITED STATES PATENT OFFICE.

SIEGFRIED MARCUS, OF PHILADELPHIA, PENNSYLVANIA.

DESIGN FOR A GLASS LIGHT.

SPECIFICATION forming part of Design No. 30,446, dated March 28, 1899.

Application filed February 27, 1899. Serial No. 707,116. Term of patent 14 years.

To all whom it may concern:

Be it known that I, SIEGFRIED MARCUS, of the city and county of Philadelphia, State of Pennsylvania, have invented and produced a new and useful Design for Glass Lights, of which the following is a specification.

My design for glass lights intended for illuminating panes or gratings is shown in the accompanying drawings, in which—

10 Figure 1 is a perspective view of a glass light embodying my design, and Fig. 2 is a transverse sectional view of the same.

The light is composed of a series of parallel parts A, each of which is triangular in cross-section and provided with one convex side a and two concave sides b c, and these parts A are united to one another at the adjacent angles of the concave side c with the interme-

diate angle d between the concave side b and the convex side a projecting outwardly, thus forming a plate having one side provided with small rounded corrugations and the other side with a series of parallel projecting concavo-convex ribs.

Having now described my design, I claim as new and desire to secure by Letters Patent—

The design for a glass light substantially as herein described and shown.

In testimony of which invention I have hereunto set my hand.

SIEGFRIED MARCUS.

Witnesses:

R. M. HUNTER,
R. M. KELLY.
